UNITED STATES PATENT OFFICE

ELISHA LEE RADER, OF OTIS ORCHARDS, WASHINGTON

DESIGN FOR A SIGN

Application filed February 18, 1931. Serial No. 38,714. Term of patent 14 years.

To all whom it may concern:

Be it known that I, ELISHA LEE RADER, a citizen of the United States, residing at Otis Orchards, in the county of Spokane and State of Washington, have invented a new, original, and ornamental Design for Signs, of which the following is a specification, reference being had to the accompanying drawings, forming a part thereof:

Figure 1 is a front elevation of a sign, showing my new design.

Figure 2 is a rear elevation; and
Figure 3 is a side elevation.

I claim:

The ornamental design for a sign substantially as shown.
